WINDING KEY FOR COLLAPSIBLE WALL TYPE CONTAINERS

John E. Regan, Elmhurst, N.Y.

Application April 18, 1958, Serial No. 729,381

2 Claims. (Cl. 222—99)

This invention relates generally to a winding key for collapsible wall type tubes, and more particularly to a winding key for discharging the contents from a plastic collapsible tube, said winding key being provided with retaining bar means for preventing unrolling of the tube from a partially wound state.

A new type of collapsible wall container has recently been introduced into commerce in this country wherein the walls of the container are formed from a plastic material such as polyethylene or the like as distinguished from the well-known thin-walled metal toothpaste tube. Such plastic tubes have been used to contain toothpaste, glue, sun tan lotion, decorative cake frostings and many other fluid and semi-fluid products. One problem which arises from the use of these plastic walled containers is that the wound end of a partially discharged container has a tendency to unwind and resume its original tubular configuration due to the restoring force inherent in the plastic material. This unwinding is very undesirable since it is accompanied by a suction effect which tends to draw air, bacteria and other impurities into the container to contaminate and harden the contents thereof.

As a solution to this problem, the present invention was developed to provide a novel winding key for rolling up the bottom of a collapsible walled container, said winding key being provided with retaining bar means adapted to cooperate with the wall of the tube to prevent unwinding of the partially wound end of the tube.

Thus the primary object of my invention is to provide a winding key for rolling up the flat end of a collapsible wall type plastic container, said winding key having retaining bar means for preventing unrolling of the partially wound tube.

Another object of my invention is to provide a winding key having a generally tubular configuration with a longitudinal slot therein for receiving the flat end of the collapsible wall tube and provided with a retaining bar extending substantially parallel to the axis of said winding key and spaced from the key, said retaining bar preventing unwinding of the container when the end thereof is partially wound about said key intermediate the key and the retaining bar.

A more specific object of my invention is to provide a winding key having a retaining bar pivotally connected at one end thereto, said retaining bar being adapted to be pivotally displaced to a position substantially parallel to the longitudinal axis of the key and spaced from said key, the free end of said retaining bar being provided with means for connecting the same to the winding key.

Another object of my invention is to provide a winding key for collapsible wall containers and provided with a retaining bar extending parallel to and spaced from said winding key, said retaining bar being rotatably connected to said winding key.

Still another object of my invention is to provide a winding key having flanges which are pressed together

2

to seal the closed end of a plastic collapsible wall container, said winding key having retaining bar means extending substantially parallel to and spaced from said winding key and functioning to prevent unrolling of the container end from a partially wound state.

Still another object of my invention is to provide a slidably movable discharge assistant for a collapsible wall type container, said discharge assistant having a main body on one side of the flat end of the container and a retaining element portion pivotally connected to said main body and extending on the other side of said container flat end, said retaining element portion being provided with means for securing the free end thereof to said main body.

Other objects and advantages of my invention will become more apparent from a study of the following specification when considered in conjunction with the accompanying drawings in which:

Fig. 1 is a perspective view of one embodiment of my winding key integrally secured to the flat end of a collapsible wall plastic container, the retainer bar being illustrated in the disengaged state;

Fig. 2 is a perspective view of the embodiment of Fig. 1 after a portion of the contents of the container has been removed by winding motion of the winding key, the retaining bar being illustrated to be in its locking position;

Fig. 3 is a plan view of the winding key of Fig. 1 which is modified to be removably secured to a collapsible-wall plastic container;

Fig. 4 is a longitudinal sectional view taken along line 4—4 of Fig. 3;

Fig. 5 is a sectional view taken along line 5—5 of Fig. 3;

Fig. 6 is a perspective view of the key of Fig. 3 used as a sliding discharge assistant for the plastic collapsible wall container;

Fig. 7 is a perspective view of another embodiment of my winding key;

Fig. 8 is a sectional view taken along line 8—8 of Fig. 7;

Fig. 9 is a bottom perspective view of another embodiment of my winding key;

Fig. 10 is an end view of the winding key of Fig. 9; and

Fig. 11 is a partly sectioned elevational view of the embodiment of Fig. 9.

Referring now more particularly to Figs. 1 and 2, the collapsible wall container 1 has a discharge nozzle 2 at one end thereof provided with removable closure means 3. While the container may be of any suitable material—such as flexible metal or the like—the invention is particularly designed for use with containers made from the synthetic plastic materials such as polyethylene or the like, which containers have been recently introduced in commerce for the marketing of semi-fluid products such as glue, skin lotions, decorative cake frostings, and the like.

Secured to the other end of the container to close the same is the winding key 4 formed of rigid metal bent to have upstanding flanges 5 and 6 forming therebetween a longitudinally-extending slot 7. Subsequent to the filling of the container, the end portion of the tube is temporarily formed into a flat configuration, the key 4 is slipped over the flat end with the slot 7 receiving the same, and the flanges 5 and 6 are pressed toward each other to seal the end of the tube in a fluid-tight manner.

At one end the key is provided with an integral projecting portion 8 formed as a handle which may be grasped by the user's fingers to rotate the key about its longitudinal axis and thus wind up the lower end of the container

to expel the contents thereof through the discharge nozzle 2.

Pivottally connected to the key 4 adjacent the handle 8 is a rigid retaining bar 9 formed from a rod of metal, plastic or other suitable material. The retaining bar 9 of Figs. 1-6 is of a U-shaped configuration and has a pair of parallel legs 9a, 9b joined at their extremities furthermost from the pivotal connection by a transverse portion 9c. The specific structure of the key and the pivotal connection of the retaining bar thereto will be presented in greater detail below with specific reference to Figs. 3-5.

When the closure member 3 is removed and the key 4 is wound to the position illustrated in Fig. 2 to partially expel the contents from the plastic container, the retaining bar 9 may be pivoted relative to the key 4 to cause the transverse portion 9c to positively engage the end 4a of the key opposite the end having the handle 8. When the retaining bar is locked in the position illustrated in Fig. 2, leg 9b of the retaining bar will engage the container wall to oppose the restoring force inherent in the plastic material which tends to cause unwinding of the container lower portion.

Figs. 3-5 illustrate in detail the basic key of Figs. 1 and 2 which is designed to be removably secured to a standard plastic container having a closed end seam. The same reference numerals have been used on identical parts in the figures.

The key blank is punched or cut from a metal sheet and is bent by dies or other suitable forming means to have a handle portion 8 and projecting longitudinal flanges 5 and 6. Each flange has inwardly directed tab portions 5a, 6a, respectively, forming a longitudinal slot 7 adapted to removably receive the flat tube end (Figs. 3-6) or to permanently receive the flat tube end to close the same (Figs. 1 and 2). At the end of the tube opposite from the end having the handle 8, a flange 4a is bent upwardly to abut the ends of the flanges 5 and 6. The connection of the flange 4a to the remainder of the key may be along a-scored or otherwise weakened line so that the flange 4a may be removed from the key if desired to provide an opening for axial insertion of the key upon the tube. The flange 4a has a punched-out tongue 4c adapted to receive the transverse portion 9c of the retaining bar when said bar is pivoted to its locking position illustrated in Fig. 4.

As shown in Figs. 3-5 the extremities 9d, 9e of the legs 9a, 9b, respectively, of the retaining bar are bent inwardly and extend through oppositely aligned openings 4b in the key flange portions adjacent the handle 8. If desired the tips of the extremities 9e and 9d may be joined together, as for example by the weld joint 10 (Fig. 5). It will thus be apparent that the retaining bar 9 is pivotally connected to the body of the key 4 by the cooperation of the inwardly directed extremities 9d, 9e with the oppositely aligned openings 4b.

The operation of the key is identical with the operation illustrated in Figs. 1 and 2. After the flat end of the tube 1 has been removably inserted into the slot 7, the handle 8 is rotated to cause the key to wind up the tube end and expel the tube contents through the nozzle 2. When a desired quantity of the contents of the plastic container have been discharged, the retaining bar is pivoted to lock the transverse portion 9c under the tongue 4c of the end flange portion 4a. Leg 9b will engage the container wall and thus prevent unrolling of the same due to the restoring force inherent in the plastic material and consequently avoid the suction of air, bacteria and other impurities into the container.

Another application of the basic key of Fig. 3 is illustrated in Fig. 6, wherein the key 4 functions as a slidably movable discharge assistant for expelling the contents from the container. According to this application of the key, the key body is positioned on one side of the container 1 and both legs (9a, 9b) of the retaining

bar 9 are positioned on the other side of the container. After the retaining bar has been pivoted to cause the transverse portion 9c of the retaining bar to be locked against the end flange 4a, the key may be slidably displaced relative to the container 1 toward the nozzle 2 thereof to discharge the contents of the container therefrom. Due to the flat deformation of the flat portion of the tube intermediate the winding key and the retaining bar, the discharge assistant will be firmly positioned on the tube and return of the tube to its original configuration will be prevented.

Referring now to Figs. 7 and 8, another embodiment of my winding key is illustrated. The winding key body 11 is similar to the winding key body of Figs. 1-6 and is formed from a sheet metal blank to provide side flanges 12, 13 forming therebetween a slot 14 adapted to receive the flat end of the plastic container 15.

According to this embodiment of my invention the retaining bar means for preventing unrolling of a partially discharged tube comprises a metal rod 16 having a straight section 16a extending parallel with the longitudinal axis of the key body 11. One end 16b of the retaining bar 16 is wound around the key body 11 adjacent its end flange 11a, and the other end 16c of the retaining bar is wound around the key body 11 adjacent its handle portion 11b and terminates in an operating lever portion 16d.

From an examination of Fig. 8 it will be apparent that the portions 16b, 16c of the retaining bar which are wound upon the key body 11 are formed to have a non-circular configuration so that the retaining bar will not be freely rotatable about the winding key 11 but rather will have a certain degree of resistance to rotation. The base of the key 11, the flanges 12, 13 and the flange tabs 12a, 13a are arranged to form a generally polygonal configuration as shown in Fig. 8; and the cooperation of the noncircular segments of the retaining rod wound portions 16b, 16c, therewith is such as to prevent unwinding of the tube from its wound state illustrated in Figs. 7 and 8. It should also be mentioned that in this embodiment a so-called clutch action is provided for the release of the retaining bar from the winding key. Referring again to Fig. 8, it will be seen that upon rotation of the lever 16d in a counter-clockwise direction with respect to the axis of the winding key and with the straight portion 16a retained stationary, the wound end 16c of the retaining bar will be loosened somewhat in its peripheral engagement with the winding key with the result that rotation of the winding key in an unwinding direction with respect to the retaining bar straight portion 16a may be accomplished.

The operation of this embodiment may now be briefly described. After the closed flat end of the container has been inserted into the slot 14, the winding key is manually rotated by means of handle portion 11b by the user while the retaining bar 16 and the tube 15 are held stationary by the other hand of the user. After a desired quantity of the contents have been discharged from the container 15, the cooperation of the straight portion 16a of the retaining bar with the container outer wall will prevent any unwinding of the tube wound portion which would result from the restoring force inherent in the plastic tube wall. To unwind the tube, the lever 16d is rotated relative to the key 11 in a direction to cause partial unwinding of the retaining bar wound portion 16c and consequently reduce the peripheral engagement of the wound portion with the key. The key may then be readily rotated in the unwinding direction relative to the straight portion 16a of the retaining bar.

Figs. 9-11 illustrate another embodiment of my invention wherein the winding key 20 has a retaining bar 21 of plastic, metal or other suitable material pivotally connected thereto. At one end the retaining bar is split and formed into two legs 21a, 21b which straddle the winding key body. The retaining bar is pivotally con-

nected to the winding key at pivot axis 22 by any suitable means.

At the other end the retaining bar is formed to have a right angled portion 21c adapted to slidably engage the end flange 20a of the winding key to lock the free end of the retaining bar to the winding key and prevent unwinding of the plastic tube in the manner described above. If desired the right angled portion 21c may have a tab 21d inwardly directed toward the end flange 20a and adapted to be inserted into groove or slot 20b provided in the end flange 20a and the adjacent portion of the winding key body. It should be mentioned that the co-operation of the tab 21d in the slot 20b provides a certain degree of lateral stability to the retaining bar in its locked position.

In each of the pivotal embodiments of my winding key the retaining bar may be made from metal, hard rubber, plastic or other suitable material, and although the retaining bar is substantially rigid, it is so designed that a slight degree of resiliency is provided therein with the result that a slight degree of tensioning is required to fit the free end of the bar over the end flange of the key. This tensioning achieves a firm and positive locking of the retaining bar to the winding key.

Although the winding key body has been described as being formed from a metal sheet, it is also possible to manufacture the rigid body from other suitable materials, such as wood, plastics, cardboard and the like.

While in accordance with the patent statutes I have illustrated and described the best forms and embodiments of my invention now known to me, it will be apparent to others skilled in the art that certain changes and improvements might be made in the product described without deviating from the scope of my invention as defined in the appended claims.

I claim:

1. A winding key for collapsible wall type containers having a discharge opening at one end thereof and a flat extremity at the other end thereof, comprising a key body having a longitudinal slot therein adapted to receive the 40

flat extremity of said container, and a resilient retaining rod rotatably connected to said key body, a first end of said retaining rod being resiliently coiled circumferentially about said key body adjacent one end of said slot and the other end of said rod being coiled about said key body adjacent the other end of said slot, the portion of said retaining rod intermediate the coiled end portions thereof being substantially parallel to the longitudinal axis of said key body, the portion of said rod being wound having a non-circular cross-sectional configuration and the first coiled end of said rod also having a non-circular configuration to frictionally restrain rotational movement of the retaining rod relative to the key body, and means for partially uncoiling said rod first coiled end to temporarily release the frictional restraining force between the coiled end and the key body, the straight portion of said retaining bar being arranged to contact a side portion of the container when said container is wound on the key body to prevent uncontrolled unrolling of the wound portion of the container.

2. A winding key as defined in claim 1 wherein the rod first coiled end terminates in an operating lever portion extending substantially at right angles to the longitudinal axis of the key body, said operating lever constituting said means for partially uncoiling said rod first coiled end portion.
